DESIGN FOR A FISH LURE

Walter L. Adams, Akron, Ohio, assignor to The Enterprise Manufacturing Company, Akron, Ohio, a corporation of Ohio

Application March 5, 1940, Serial No. 90,688

Term of patent 14 years

To all whom it may concern:

Be it known that I, Walter L. Adams, a citizen of the United States, residing at Akron, in the county of Summit and State of Ohio, have invented a new, original, and ornamental Design for a Fish Lure, of which the following is a specification, reference being had to the accompanying drawing, forming a part thereof of which:

Fig. 1 is a plan view of a fish lure, showing the new design; and

Fig. 2 is an elevational view thereof.

The characteristic feature of my design resides in the combination on the bait body disclosed of the series of brace-like markings along the sides, in association with the dorsal strip, all as shown.

What is claimed is:

The ornamental design for a fish lure, substantially as shown and described.

WALTER S. ADAMS.
